SELF-LOCKING MOTOR CONTROL

Herald D. R. Lane, Derby, Va., assignor, by direct and mesne assignments, of one-third to Harvey W. Culbertson, one-third to Kenneth M. Lane, and one-third to Will H. Nickels, all of Gate City, Va.

Application February 13, 1935, Serial No. 6,369

6 claims. (Cl. 74—565)

This invention relates to a self-locking motor control.

An object of my invention is the provision of efficient and simple means for preventing accidental operation of the handle of a motor control.

Another object of my invention is the construction of a handle device of a motor control, which will automatically cause a latch to be moved when the operator manipulates the handle, but when the handle is idle, the latch will move to a locking position, whereby the handle cannot be accidentally moved or turned.

With the foregoing and other objects in view, my invention comprises certain novel constructions, combinations and arrangements of parts as will be hereinafter fully described, illustrated in the accompanying drawing, and more particularly pointed out in the appended claims.

20 In the drawing:

Figure 1 is a vertical, central, sectional view of a device constructed in accordance with the present invention, while

Figure 2 is a view in elevation of the same.

25 Figure 3 is a top plan view of the device.

Figure 4 is a horizontal sectional view taken on line 4—4, Figure 1, and looking in the direction of the arrows.

Figure 5 is a vertical, sectional view of the top 30 part of the control box, showing in elevation the inside of the fixed section of the housing thereon.

Figure 6 is a perspective view of the dog or latch and a portion of the motor-control shaft and the handle.

35 Figure 7 is an inverted perspective view of the dog or latch.

Referring to the drawing by numerals, 1 designates the control box of any ordinary type in which is positioned the usual post or shaft 2.

40 This shaft 2 projects above the top 3 of the control box 1.

On the top 3 is a housing 4 which comprises a fixed section 5 and a hinged section 6; these sections are connected by hinge 7 (Fig. 4). A hasp 8 and lock 9 of any efficient type is used to prevent tampering or fraudulent examining of the interior of the housing.

The shaft 2 extends up into the housing 4, with its upper end 10 bevelled, as shown in Fig. 1. A handle 11 is provided on its inner end with a large socket 12. The upper bevelled end of shaft 2 extends into this socket 12 (Fig. 1). A bolt 13 extends through the socketed end of handle 11 and through shaft 2, pivotally connecting the handle to the shaft. On the inner socketed end

of the handle is formed an integral lip 14; this lip projects outwardly over the finger 15, that extends upwardly from the inner end of the dog or latch 16, which latch rests directly on the top 3 of the control box. This latch 16 is provided near its inner end with an elongated slot 17, which permits the latch to pivot in a vertical plane and be loosely mounted upon the shaft 2; the end of the shaft in housing 4 is angular (Fig. 4), which prevents the loosely mounted latch 16 rotating upon shaft 2. On the under face of latch 16 and at its outer end it is bevelled at 18 (Fig. 7), so as to facilitate the outer end of latch 16 passing up the inclined groove 19, from off the top 3. At the inner end of groove 19 (Fig. 5) is a 15 large pocket 20 having an overhanging shoulder 21. Normally the outer end of latch 16 will drop into this pocket and will be held therein if any portion of the latch is under shoulder 21.

In operation when the motor is inactive, the 20 handle will be in the position shown, with the latch 16 in its locking position. By accidentally striking against the handle, the latch at its outer end will only move horizontally in pocket 20. To officially operate the device, the operator grasps 25 grip 11a, raises upwardly thereon, which causes the handle to pivot on bolt 13, moving lip 14 downwardly, forcing finger 15 outwardly, thereby lifting the outer bevelled end of latch 16 upwardly, to the top of pocket 20. Then by the operator 30 exerting a rotary motion to the left, the latch will move down the inclined groove 19, and then will travel to the desired position for starting the motor. The handle cannot make a complete revolution for upon continued rotation of the 35 same, the latch 16 will move into groove 22 of the hinged section 6 and then into the socket or groove 23 of the fixed section 5 (Fig. 5); when the outer end of the latch 16 strikes the inner end of socket 23, it will stop rotary movement of the 40 handle. Then by the operator reversing the rotary movement, he can cause the latch to eventually drop into the locking position, in pocket 20.

I have found from practical experience with a 45 working model that my device is very efficient. It is simple to operate and is positive in action. The handle acts as weighted, for upon the operator releasing same, it moves close to the top 50 of housing 4, which permits the latch to freely fall into its locking position in pocket 20. However, by the operator lifting up on the outer end of the handle, the latch can be quickly and easily moved from its locking position, for placing the 55

motor control in an operative position, whereby the motor is allowed to start.

While I have described the preferred embodiment of my invention and illustrated the same in the accompanying drawing, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In a device of the class described, the combination with a control box, of a housing on top of said control box, a shaft extending into said housing, a latch in said housing and loosely mounted on said shaft, said housing provided in its side only with means for receiving part of said latch in a locked position or in an unlocked position, and a handle pivotally mounted on said shaft and engaging said latch for operating the same.
2. In a device of the class described, the combination with a control box provided with a top, of a housing on said top, said housing comprising a fixed and a hinged section, said fixed section provided with an inclined groove opening at its outer end level with the upper face of said top, said fixed section provided at the inner end of said inclined groove with a large pocket having an overhanging shoulder, said fixed section provided contiguous to said top with a horizontal socket, said hinged section provided with a groove registering with said horizontal socket, a shaft extending vertically into said top through said housing, said shaft being bevelled on its upper end, a latch provided with an elongated slot, said shaft extending through said slot, said latch provided with an upwardly and outwardly extending finger at its inner end, said latch being bevelled transversely on its inner face at its outer end, said latch adapted to travel over the top and having its bevelled portion rise easily up said inclined groove, said bevelled end adapted to rest in said large pocket and under said shoulder, a handle provided at its inner end with a large socket, said bevelled end of said shaft extending into said socket, whereby the handle can move upon said shaft, said handle provided with a horizontal lip overhanging and engaging the finger of said latch, whereby vertical upward movement of the

handle will cause vertical movement of the outer end of said latch, and a bolt extending through the socketed portion of said handle and said shaft for pivotally mounting the handle on said shaft, substantially as shown and described.

3. In a device of the class described, the combination with a control box, of a housing on top of said control box, a shaft extending into said housing, a latch loosely mounted on said shaft and resting part of the time directly in contact with said control box, means on said housing for receiving said latch in a locking position, and a handle pivotally secured to the outer end of said shaft within said housing and capable of operating said latch.

4. In a device of the class described, the combination with a control box, a housing on said control box, a shaft extending into said housing, of a latch movably mounted on said shaft, said housing being provided with a locking groove-structure in its side, said latch having one end always in said groove-structure for locking the latch or permitting same to be moved to an unlocked position, and a handle pivotally mounted directly on said shaft within said housing and engaging said latch for operating the same.

5. In a device of the class described, the combination with a control box, of a housing on said control box, said housing provided with a groove-structure including a locking pocket, a shaft extending into said housing, a latch movably mounted in said housing and having one end always seated in said groove-structure and adapted to be positioned in said pocket, and a handle carried by said shaft and cooperating with said latch for moving the same to a locked or unlocked position.

6. In a device of the class described, the combination with a control box, of a housing on said control box, said housing provided in a part of its vertical side walls with a cam-like groove having at one end a pocket and opening at its other end upon said control box, a latch in said housing and having a portion at all times in said cam-like groove and adapted to be seated in said pocket, and a handle cooperating with said latch for moving the latch out of said pocket and along said groove and onto the top of the control box or vice versa.
